LOCKING MEANS FOR ROTARY OPERATING BARS OF DOOR FASTENERS

George E. Dath, Mokena, Ill., assignor to W. H. Miner, Inc., Chicago, Ill., a corporation of Delaware

Application October 10, 1947, Serial No. 779,154

4 Claims. (Cl. 292—218)

1

This invention relates to improvements in holding means for locking the rotary operating bar of a door fastener in position to hold the door closed.

One object of the invention is to provide simple and efficient means for locking the lever operated rotary bar of a door fastener in position with the door closed.

A more specific object of the invention is to provide in a door fastener of the lever operated type, a latch member rotatably supported on the bar for swinging movement in a plane parallel to the bar and arranged to be turned to a position crosswise of said bar to block the latter against rotation in door opening direction by engagement with a fixed abutment plate on the door.

Other objects of the invention will more clearly appear from the description and claims hereinafter following.

In the accompanying drawing forming a part of this specification, Figure 1 is an elevational view, partly broken away, of the lower portion of one of the side walls of a railway car provided with the usual hinged doors and rotary door fastener, illustrating my improvements in connection therewith. Figure 2 is a horizontal sectional view, on an enlarged scale, corresponding substantially to the line 2—2 of Figure 1. Figure 3 is an elevational view, looking upwardly in Figure 2. Figure 4 is a vertical sectional view, corresponding substantially to the line 4—4 of Figure 3. Figure 5 is a view, similar to Figure 3, showing the latch member turned parallel to the bar to unlock the bar for rotation.

In said drawing, 10 indicates the side wall member of a railway car provided with an opening 11, closed by a pair of hinged doors 12 and 13. As is common practice, the doors 12 and 13 are beveled at their inner meeting edges, the door 12 overlapping the door 13 to hold the latter closed. The door 12 carries a rotary door fastener mechanism of well-known design for forcing the door 12 closed and prying the same partly open, comprising a rotary operating bar 14, having keeper engaging crank members at the top and bottom ends cooperating with fixed keepers on the car wall above and below the door opening, only the lower keeper engaging crank member 15 and the lower keeper 16 being shown in the drawing. The bar is supported by top, intermediate, and bottom bearing brackets fixed to the door 12, the intermediate and bottom brackets only being shown, the same being indicated by 17 and 18, respectively. The bar 14 is provided with the usual operating lever 19, which is fixed to the outer side

2

of the bar, as shown in Figure 1, below the intermediate bearing bracket 17. The lever 19 is of the fixed type, being rigid with the bar and projecting laterally at right angles therefrom.

5 My improved locking means comprises broadly a rotary latch member or bar A, supported on the bar 14, and a cooperating abutment or stop plate B fixed to the outer side of the door.

The rotary latch member A, which is shown in 10 Figures 1 to 5 inclusive, as fixed to the back of the bar, is in the form of an oblong plate, swingingly supported between its ends by a pivot member or pin 20 in the form of a rivet which extends through the member A, the bar 14, and the inner 15 end or head 21 of the lever 19, this rivet also acting as a securing element to fix the lever to the bar. The lever is further secured to the bar by a second rivet 22 above the rivet 20. The latch member A corresponds in width to the bar 14 so 20 that when it is turned to a vertical position, as shown in Figure 5, it is aligned with the bar.

The abutment or stop plate B is of greater 25 length than width, and as shown in Figures 1, 2, 3, and 5, is fixed to the outer side of the door 12 to the right of the bar 14 by screws 23—23. As shown, the plate B is preferably arranged vertically in parallel relation to the bar and has its lower end slightly beveled off at the outer side, as indicated at 24.

30 Provision is made for sealing the latch member in the locked position shown in Figures 1 and 2, the handle lever 19 and the latch member being provided with cooperating perforated seal receiving lugs 25 and 26, adapted to accommodate the usual car seal, the lug 25 projecting laterally outwardly from the lower side of the lever 19 and the lug 26 projecting laterally outwardly from the upper side of the latch member A.

In the locked position of the fastener, the latch 40 member A extends transversely of the bar 14, as shown in Figures 1, 2, 3, and 4, with its right hand end abutting the plate B. In this position of the parts, the latch member A, by engagement with the plate B, effectively locks the bar 14 45 against rotation in door opening direction. In this transverse position of the latch member A, the sealing lug 25 of the lever and lug 26 of the latch member are in alignment with the perforations thereof registering to receive the usual 50 car seal.

To unlock the bar 14 for rotation by the operating lever 19 to force the door open, the latch member A is turned from the transverse position shown in Figures 1, 2, 3, and 4 to the vertical position 55 in alignment with the bar 14, as shown in

Figure 5, thereby freeing the bar to be rotated by swinging movement of the lever 19 outwardly away from the door 13 toward the right and over the door 12.

In closing the door 12, the operating lever 19 is swung from right to left, back to the position shown in Figures 1, 2, and 5, thereby camming the door 12 shut. To lock the door fastener against movement in door opening direction, the latch member A is turned from its vertical position shown in Figure 5 to its transverse or horizontal position, as shown in Figures 1, 2, 3, and 4, into overlapping relation with the abutment plate B, tight engagement with this plate being facilitated by camming engagement between the latch member and the beveled face 24 at the lower end portion of the abutment plate B over which the end of the latch member A rides in being turned to its horizontal position.

I claim:

1. In a door fastener, the combination with a bar rotatably mounted on the door and having keeper engaging means thereon engageable with fixed keeper means; of an elongated latch plate pivoted between its ends on said bar for turning movement about an axis at right angles to the length of the bar, said plate being turnable to position the same in either lengthwise alignment with the bar or crosswise thereof, said plate when turned to its position crosswise of the bar blocking said bar against rotation by engagement with the door.

2. In a door fastener, the combination with a bar rotatably mounted on the door and having keeper engaging means thereon engageable with fixed keeper means; of an elongated latch plate pivoted between its ends on said bar for turning movement about an axis at right angles to the length of the bar, said plate being turnable to position the same in either lengthwise alignment with the bar or crosswise thereof; and an abutment plate fixed to the outer side of said door with which the latch plate in its position

crosswise of the bar is engageable to hold said bar against rotation.

3. In a door fastener, the combination with a bar rotatably mounted on the door and provided with keeper engaging means cooperating with fixed keepers; of an operating lever fixed to said bar for rotating the same, said lever extending at right angles to said bar in a plane parallel to the length of the latter; an elongated latch plate pivotally connected between its ends to said bar for rotation about an axis normal to the plane of said bar, said plate being turnable from a position parallel to and in lengthwise alignment with the bar to a position transverse of said bar with its opposite ends projecting beyond opposite sides of the bar, one end of said plate in said transverse position thereof engaging the outer side of the door to block rotation of the bar; and perforated cooperating seal receiving lugs on said lever and other end of said plate, said lugs being brought into registration to receive a car seal when said plate is turned to said position transverse of the bar.

4. In a door fastener, the combination with a vertically disposed rotary operating bar on the outer side of said door; of means actuated by rotation of said bar in reverse directions for moving said door into and out of the door opening; and a latch plate on said bar pivotally connected to the same for turning movement about an axis at right angles to the length of said bar, said plate being turnable to two different positions with respect to said bar, said plate in one of said positions being in lengthwise alignment with the bar to clear the door and permit rotation of the bar, said plate in the other of said positions being disposed crosswise of the bar with one of its ends projecting from the side of the bar to block rotation of the latter by engagement with the outer side of the door.

GEORGE E. DATH.
